FLUID MIXING VALVE FOR SHOWERS OR THE LIKE

Clifford Lewis Barker, Cheltenham, England, assignor to Walker, Crosweller & Company Limited, Cheltenham,
England, a British company

Filed Aug. 30, 1966, Ser. No. 3,650

Claims priority, application Great Britain Mar. 25, 1966

Term of patent 14 years

(Cl. D91—3)

FIGURE 1 is a perspective view taken from the top, front and one side of a fluid mixing valve for showers or the like, showing my new design;

I claim:

The ornamental design for a fluid mixing valve for showers or the like, as shown and described.
